UNITED STATES PATENT OFFICE.

JOHN BURKHARDT, OF NEW YORK, N. Y., ASSIGNOR OF ONE-HALF TO
WILLIAM H. JACKSON & CO., OF SAME PLACE.

METHOD OF FORMING ORNAMENTAL STUDS OR PILLARS.

SPECIFICATION forming part of Letters Patent No. 378,414, dated February 21, 1888.

Application filed March 4, 1887. Serial No. 229,708. (No model.)

To all whom it may concern:

Be it known that I, JOHN BURKHARDT, of New York, in the county and State of New York, have invented a new and useful Method 5 of Forming from Metal Tubing Certain Ornamental Studs, Little Pillars, and Similar Articles for Various Uses; and I hereby declare that the following is a full, clear, and exact description thereof, reference being had 10 to the accompanying drawings.

In the drawings, Figure 1 represents a perspective view of a stud or little pillar formed of tubing by my new method. Fig. 2 represents a perspective view of a piece of tubing 15 embraced by a yoke or pillow-block in readiness for the action of a pair of dies to be operated by a power-press. Fig. 3 represents a vertical section of a pair of dies, the clamping-yoke shown in Fig. 2, and a piece of tubing, and shows the form to which the latter 20 is reduced by the first compression and pair of dies. Fig. 4 is a vertical central section of the tube, the yoke, and a different pair of dies, and shows the form of the completed 25 stud after the action of the modified dies thereon, also shown in Fig. 1. Fig. 5 represents a modified form of a lower die to be used with one of the dies shown in Fig. 4, for the reduction of a short tapering piece of 30 tubing to the shape of the pedestal, represented in Fig. 6 as supporting a globe. Fig. 7 represents a side elevation of the stud or little pillar as supporting a part of a grate-fender mounted with globes or balls.

35 My present invention relates to the subject of forming ornamental metal spheroidal bodies from tubing, described in my applications for patents filed January 3, 1887, and the product thereof is intended to be used in 40 connection with the articles designated in said applications.

In the drawings, A denotes a piece of metal tubing embraced by a clamping yoke or collar formed in two parts or jaws, B C, and 45 secured by the hinged removable clasping-bars D.

E E' are a pair of dies made with central cylindrical projections, a, and an annular recess, d, with rectangular shoulders, and H H' 50 denote a pair of dies similar to dies E E', ex-

cepting that, instead of being formed with rectangular shoulders, the outer shoulders are rounded to form a quarter-circle, as shown in Figs. 4 and 5.

The interior of the yoke B C may be either 55 cylindrical or of tapering form, increasing in diameter from the center of the opening to the ends through which the ends of the tube A project, and thus made said interior will correspond in form with the shape indicated 60 by dotted lines in Fig. 1.

By the use of the die H and the modified die J, Fig. 5, the pedestal K, Fig. 6, may be formed from a tapering piece of tubing.

To form studs or pillars by the use of the 65 mechanism described above the upper die, E, will be attached to the slide or plunger of a power-press, and its counter-die E' will rest upon the platen or seat of the press directly under the die E, and the piece of tubing 70 embraced by yoke B C will be placed in a vertical position between the dies, resting in die E', as seen in the drawings. The first downward movement of the die E, actuated by the press, will be limited, either by a suitable stop or by the manipulation of the operator, to arrest the descent, after having formed 75 by compression the collars or rings i i directly above and below the yoke B C. At this stage of the process dies H H' will be substituted 80 in place of dies E E', and a second operation of the press will be made in like manner, and this second compressive action upon the tube A will cause the dies H H' to form the collars g g around the ends of the tube A, completing 85 the article. The body of the tube A between the two collars i i will by the compressing action be forced into the form of the interior of yoke B C.

It should be observed that the compressive 90 force upon the piece of tubing will cause the collars or rings formed simultaneously thereby to be of corresponding shape and size at each end of the stud or pillar. Of course one collar may be formed at one end of the stud 95 and two or more at the other end.

Having described my invention, what I claim therein, and desire to secure by Letters Patent, is—

The method herein described of forming 100

studs, pillars, or pedestals, which consists in first forming the metal into a tube, then placing the tube in the yoke or clamp B C, then placing the tube with the yoke around it between an-
5 nular dies E E' and compressing it, forming the collars or rings i i, and then placing the tube with the yoke around it between the dies H H' and compressing it between them,

forming the collars g g around the ends of the tube, and at the same time compressing the central portion of the tube into the form of the interior of the yoke or clamp B C.

JOHN BURKHARDT.
